UNITED STATES PATENT OFFICE.

ALFRED SEYFFERTH, OF CHICAGO, ILLINOIS.

CONCRETE GARBAGE CAN.

Application filed February 6, 1922. Serial No. 534,387.

To all whom it may concern:

Be it known that I, ALFRED SEYFFERTH, a citizen of the United States, residing at Chicago, in the county of Cook and State of Illinois, have invented a certain new and useful Improvement in Concrete Garbage Cans, of which the following is a full, clear, concise, and exact description, reference being had to the accompanying drawings, 10 forming a part of this specification.

My invention relates to refuse receptacles, and more particularly to a concrete garbage can.

It is a purpose of the invention to provide 15 a concrete refuse receptacle of the character referred to above which is made up of a base section and a top section, said sections being preferably made with wall portions having the opposite faces thereof made in 20 such a form that the top section can be set on the base in any desired position. The opposite faces are provided with interlocking means whereby the top section is held in any desired position on the base.

25 It is a further purpose of the invention to provide a refuse receptacle of the character referred to above which is provided with a floor therein which slopes from the edges thereof toward the middle, thus preventing 30 the leakage of any liquid from the receptacle at the doors or side edges thereof.

It is still a further purpose of the invention to provide a hinged cover for a receptacle of the above mentioned character 35 which is provided with a handle having integral means thereon which acts as a stop for limiting the opening movement of the cover and to provide a cover that overlaps the material of the receptacle adjoining the 40 opening which the cover closes in such a manner as to substantially seal the opening.

It is another object of the invention to 45 provide a refuse receptacle with an opening in the side thereof which is closed by means of a door preferably hinged at the top of the opening, and to provide a facing for said opening, of metal, which will prevent the breaking away of the corners of the concrete by engagement of a shovel with the 50 concrete when the shovel is inserted through the opening. Said facing or reinforcement is preferably made of angle iron, one leg of the angle overlying the outer face of the receptacle and the other leg thereof 55 overlying the wall of the opening.

It is also an object of the invention to

provide new and improved means for fastening a hinge carrying member to the concrete body portion of a receptacle of the above mentioned character, which comprises 60 a headed member mounted in the concrete and having a locking member, such as a nut, screwthreaded thereon and embedded in the concrete, and having a second locking member, such as a nut, mounted thereon 65 which clamps the hinge carrying member between said nuts.

Other objects and advantages of the invention will appear as the description of the accompanying drawings proceeds. 70 However, I desire to have it distinctly understood that I do not intend to limit myself to the exact details shown or described, but that I intend to include as part of my invention all such obvious changes and 75 modifications of parts as would occur to a person skilled in this art, and as would fall within the scope of the claim.

In the drawings:

Fig. 1 is a side elevation of my improved 80 concrete garbage can;

Fig. 2 is a vertical sectional view thereof;

Fig. 3 is a top plan view of the garbage can showing the top in one position in full lines and in another position in dotted lines; 85 and

Fig. 4 is a fragmentary sectional view showing the means for anchoring the hinge-carrying plates to the concrete body portion 90 of the receptacle.

Referring in detail to the drawings, the improved refuse receptacle comprises a base portion 5 and a top portion 6, the base portion 5 being provided with a bottom or floor 8 and with side walls 9. One of said side 95 walls 9' is provided with a projecting portion 10 having an inclined front wall 11 and having an opening 12 therein. The top section 6 is provided with side walls 13 and with an inclined top portion 14 terminating 100 in a raised flange or rib 15 extending around the opening 16 in said top.

Mounted on the top is a cover member 17 which is provided with the downwardly turned edge portion or bead 18, which embraces the rib or rim 15 to provide a substantially tight closure between the cover 17 and hinged at 19 to the plate 20, said plate 20 being secured to the member 6 by means of the bolts 21. As will be seen from Fig. 4, 110 the plate 20 is securely held in position in the concrete of the member 6 by means of

the bolt 21 which is provided with a head 22 embedded in the concrete and with a nut 23 which is screw threaded on the screw-threaded portion 24 of the bolt, and which 5 is also embedded in the concrete, and which is provided with a nut 25 cooperating with the screw threads 24 to clamp the plate 20 to the top member 6. Secured to the cover 17 by any suitable securing means, such as 10 to the rivets 26, is the handle 27, which is provided with an integral rearwardly extending finger 28 which is adapted to engage with the top 14 to limit the opening movement of the cover 17. The top section 15 6 is provided with a groove 29 on the lower end portions or faces 30 of the walls 13 which are adapted to receive the tongues 31 on the corresponding upper end portions or edges 32 of the walls 9 and 9' of the base 20 member 5. The base member 5 is provided with an angle iron frame comprising the leg or portion 33 which embraces a portion of the inclined wall 11 adjacent the opening 12 and the leg or portion 34 which faces a 25 portion of the wall 35 of the opening 12, so as to protect the corner formed at the junction of the walls 11 and 35 so as to prevent the concrete at the corner from being broken away by engagement of the shovel 30 used for emptying the refuse out of the receptacle therewith. The frame is secured to the concrete by means of the bolts 21' in a similar manner to that in which the plate 20 is secured to the concrete by means 35 of the bolts 21. The door 36 is hinged to the bolts 33 of the frame by means of the hinges 37, and is provided with a hook 38 which engages with the lug 39 to hold the door in closed position. The bottom 8 of 40 the base member 5 is provided with a floor having the inclined portions 40 which slope from the side edges thereof toward the center 41 of the floor. In this manner all liquid in the receptacle will flow toward the 45 center of the receptacle instead of toward the side edges of the bottom thereof, thus

preventing leakage of the same through the doors.

It will be seen that due to the fact that the opposite faces of the side walls 9, 9' and 50 13 are made of the same shape and of the same dimensions, and due to the fact that a tongue and groove connection is provided for anchoring the top to the base, the top section of the receptacle can be placed in 55 any desired position on the bottom or base, thus for example, if desired, the top section can be so placed on the base that instead of the hinges for the cover 17 being on the same side of the cam as the door 36, as shown in Fig. 3 in full lines, the same can be placed in a directly opposite position and if desired, the top can be placed in such a position that the hinges of the cover are placed as shown in dotted lines in Fig. 3, or in the 60 position directly opposite to that shown in dotted lines, thus making it possible to have the top open in any desired direction that is convenient for emptying refuse into the receptacle. 70

Having thus described my invention, what I desire to claim and secure by U. S. Letters Patent is:

A concrete refuse receptacle having an opening therein, a door for closing said opening, hinges for said door, a metallic frame on which said hinges are mounted and bolts permanently embedded in said concrete for securing said frame in position, said bolts having heads embedded in said concrete, locking members screwthreadedly engaging the same, said members being embedded in said concrete flush with the surface thereof, and means screwthreadedly engaging the portions thereof projecting from said concrete for detachably clamping said frame in position on said concrete and in engagement with said locking members. 75 80 85

In witness whereof, I hereunto subscribe my name this 31st day of January, A. D. 90 1922.

ALFRED SEYFFERTH,
